TRESTLE ASSEMBLING DEVICE

Filed June 19, 1929

BY *J* ATTORNEYS

UNITED STATES PATENT OFFICE

CHRISTIAN T. STRAND, OF LOS ANGELES, CALIFORNIA

TRESTLE ASSEMBLING DEVICE

Application filed June 19, 1929. Serial No. 372,179.

This invention relates to trestles, and more especially to that type of trestle or sawhorse ordinarily employed by mechanics for supporting material while various operations such as sawing and the like, are performed thereupon.

An object of the invention is the provision of a novel and unusually efficient trestle or sawhorse of this general type, which is so constructed that it is capable of being folded for the purpose of facilitating transportation or stowage thereof.

Another object is the provision of a foldable trestle as described, which, when extended to operative position, presents an extremely rigid structure, thereby producing a horse which is a decided improvement over the conventional non-folding horse, inasmuch as the latter practically invariably becomes unstable after having been in service for any appreciable length of time.

A further object is the provision of an assembling device for a folding trestle, which is of very simple nature, and hence relatively inexpensive to manufacture and easy to apply, and which may be employed by the ordinary carpenter or other mechanic as a means of inter-connecting the body bar and legs of an otherwise conventional sawhorse. In respect to this object, the assembling device is designed with the idea in mind of facilitating the transportation of the horse after completion, from place to place. Heretofore, it has been customary for a carpenter to construct a new sawhorse whenever he starts work upon a new location, and to discard the horse after that particular job has been completed. Obviously, this procedure is relatively expensive, inasmuch as it entails a waste of both time and material. Furthermore, inasmuch as such a sawhorse is usually constructed as quickly and as cheaply as possible, this conventional type of non-folding horse, is more or less unsatisfactory, inasmuch as the joints between the body bar and legs, soon work loose, permitting the entire structure to wobble, which obviously detracts from the efficiency of the workmen employing the structure. Furthermore, the legs being attached to the sides of the body bar by

nails, continued use of the horse results in these nails working loose, permitting the upper ends of the legs to project slightly beyond the upper face of the body bar, thus destroying the previously level surface thereof, and resulting in considerable inconvenience, inasmuch as boards and other articles will not lie perfectly level when supported thereupon. It is with the purpose of eliminating all these undesirable features of the conventional sawhorse, that the assembling device of the present invention, has been developed.

Another object is the provision of an assembling device as described, in which no part thereof other than those portions actually disposed between the legs of the trestle, is of greater width than the ordinary sized body bar employed for such saw horses. The purpose of this detail of construction is to avoid the danger of contact of edged tools such as a saw or chisel, with the metal of which the assembling device is constructed.

The invention possesses other objects and advantageous features, some of which, with those enumerated, will be set forth in the following description of the invention's particular embodiment which is illustrated in the drawing accompanying and forming a part of the specification.

Referring to the drawing:

Figure 1 is an end elevation of a trestle, in the construction of which the improved assembling device of the present invention, has been employed. Portions of the figure are broken away to reduce its length; and the direction of view is indicated by the arrow 1 of Fig. 2;

Fig. 2 is a view in side elevation, of the trestle of Fig. 1. But one end of the trestle and the upper end of an associated leg are shown, in order to reduce the size of the figure;

Fig. 3 is a view similar to Fig. 2, but showing the parts moved to those positions occupied thereby when the trestle is folded;

Fig. 4 is a perspective view of the leg-attaching member;

Fig. 5 is a perspective view of a slightly modified form of leg-attaching member;

Fig. 6 is a perspective view of the brace and

its means of attachment to the trestle. Portions of the figure are broken away to reduce its length.

Specifically describing the assembling device in the most practical embodiment thereof of which I am at present aware, it is composed of two essential parts, to wit: the leg-attaching member 11 or 11' shown in detail upon Figs. 4 and 5 respectively, and the bracing member 12 shown in detail upon Fig. 6. These two members are employed for releasably and rigidly retaining in operative position, the substantially horizontally disposed body bar 13, which is preferably composed of wood or other non-metallic material, and the supporting legs 14 therefor.

The bracing member 12 comprises a rigid strip 16 pivotally attached as by a rivet or other suitable pin 17, to an attaching member 18 of any suitable description. As shown, the brace-attaching member 18 comprises a relatively short length of angle iron, one leg 19 of which is provided with holes 21 through which screws or their equivalent may be driven into the under face of the body bar 13, to rigidly attach the attaching member 18 thereto. The other leg 22 is provided with a single aperture through which the pin 17 extends in order to pivotally attach the strip 16 to the attaching member 18.

The brace-attaching member 18 should be secured to the under face of the body bar 13, at a point spaced a considerable distance from that at which the legs 14 are attached, as best shown upon Fig. 2. This permits the strip 16 to be so disposed that it inclines downwards toward the legs 14, between which is positioned a cross bar 26. This cross bar is rigidly attached to the lower end of the strip 16, as by rivets 26' or their equivalent—the lower end of the strip 16 being disposed medially of the cross bar 26. Each end of the cross bar 26 is deflected to provide an attaching flange 27, each of which is provided with an angularly disposed slot 28, wherein a bolt 29 may be accommodated so as to fasten one of the legs 14 to each flange 27, a wing nut 30 or its equivalent being provided upon each of the bolts 29, to permit tightening. Inasmuch as the legs 14 diverge as they extend downwards from the bar 13, the cross bar 26 is elongated, and the flanges 27 are each disposed at an acute angle with the body portion of the cross bar 26, as clearly shown on Fig. 2.

The bracing member 12 is also provided with a strap 31 rigidly secured to the strip 16 intermediate its ends, as by rivets 32 or their equivalent. The strap 31 extends on both sides of the strip 16, thus providing a finger on each side thereof, against which a saw, square, or other tool may be leaned, and thus afford convenience to the user by retaining such tools easily accessible.

Flanges 33 are formed by bending both

ends of the strap 31 upwards; and it is found that these flanges aid in retaining the tools as placed. Preferably the rivets 32 are not positioned at the center of the strap 31, with the result that one of the fingers is longer than the other; the purpose being to design the strap so that the longer finger is of sufficient length to accommodate the handle of a saw or other tool of equal thickness, whereas the shorter finger will accommodate a relatively thin square.

The leg-attaching member 11 comprises spaced angular members 36, each comprising a horizontal flange 37 and a flange 38 extending downwards therefrom at an acute angle therewith. These two members are retained in spaced relationship by means of an inverted U-shaped strap 39 to which the members 36 are rigidly attached as by rivets 40 or their equivalent. The U-shaped strap 39 is so constructed that the legs 41 thereof, flare downwards at an angle equal to the angle at which it is desired that the legs 14 diverge; and the parts are so proportioned and arranged that the flanges 38 of the members 36 diverge at this same angle when the attaching member 11 is assembled. Holes 42 are provided in the horizontal flanges 37 which are in horizontal alignment, thereby permitting the attaching member 11 to be rigidly attached to the under face of the body bar 13, by screws or their equivalent. A single hole 43 is formed through the lower end of each of the legs 41 of the strap 39, and through the adjacent portion of the associated flange 38, thus permitting the insertion of a fastening bolt 44 having a wing nut 45 thereupon, and by means of which a leg 14 may be pivotally attached to each of the leg flanges 38.

A slightly modified form of leg-attaching member 11' is disclosed upon Fig. 5. Here the leg flanges 38' are retained in spaced relationship by means of their end flanges 46. The flanges 46 of both leg flanges 38', are rigidly interconnected by rivets 47 or their equivalent. This attaching member 11' may be constructed of two identical die stampings, with the result that it is relatively inexpensive to construct. With the exception of the substitution of the end flanges 46 for the U-shaped strap 39 of the other modification, the attaching member 11' is identical in construction and manner of employment as that previously described.

Whereas the figures show but one end of a trestle constructed by means of my improved assembling device, it will be readily understood that I contemplate employing a pair of legs 14 secured adjacent each end of the body bar 13, by means of one of the attaching members 11, or 11', and each pair of legs 14 being provided with a bracing member 12.

The trestle is extended to operative position by swinging the legs 14 downwards from the position shown upon Fig. 3, until they have

slightly passed positions of perpendicularity with the horizontally disposed body member 13. If the inner upper corner of each leg is rounded as at 51, to present an arc about a center coincident with the axis of the bolt 44 by which the leg is attached to the attaching member 11, and the outer upper corner 52 cut so that the corner 52 comes in contact with the under face of the associated horizontal flange 37 when the leg has been moved to extended position as indicated upon Fig. 2, a much more rigid structure will be produced. After each leg 14 has been moved to this position, the bracing member 12 should be so disposed that the bolts 29 pass through the slots 28 in the flanges 27 of the cross bar 26, whereupon the wing nuts may be tightened to rigidly secure the bracing member 12 in position.

When so assembled, it will be found that the resultant horse is extremely rigid, devoid of any possible end sway or other movement in which the legs 14 and body bar 13 shift in respect to each other. This rigidity obviously will result in the great convenience afforded to the user.

Another feature which should be here mentioned, is that the assembling device does not project beyond the sides of the horizontally disposed body bar 13. This feature is of importance inasmuch as it precludes the possibility of the user's inadvertently permitting his edged tools such as saws, chisels and the like, from coming in contact with any metal parts of the horse. The only metal portions of the entire structure which are not entirely below the horizontal bar 13, are the cross bar 26 and the heads of the bolts 29 and 44; and inasmuch as these portions of the device are actually in the plane of both associated legs 14, there is no danger of edged tools coming in contact therewith before first encountering the wood of which the legs 14 are ordinarily constructed.

When it is desired to fold the trestle, the wing nuts 30 should be loosened, permitting disengagement of the cross bars 26 from their associated legs 14. The legs 14 may then be folded into substantial parallelism with the body bar 13; and the bracing member 12 may be folded up against the under side of the body bar 13, this position being indicated upon Fig. 3. The strip 16 forming the body portion of the bracing member 12, should be of such length and should have its pivoted end so positioned with respect to the associated leg-attaching member that when the trestle is folded the crossbar 26 will be positioned beyond the upper ends of the associated legs 14. The upper ends of these legs become exposed at the end of the trestle when the legs are folded up against the under face of the bar 13, and will be protected by the crossbar 26 against injury during transportation of the trestle in folded arrangement.

This is important inasmuch as the distance from the upper end of each leg to the center of the aperture through which the associated pivot bolt extends should be exactly the distance between the center of the bolt and the under side of the associated flange 37 in order to impose the weight of the body bar 13 directly upon the ends of the legs when the trestle is in erected arrangement. Hence, any burring or roughening of the upper ends of the legs would either make it difficult or impossible to swing the legs to extended position, or would result in imposing the weight of the body bar 13 upon the pivot bolt 44 instead of upon the end of the leg. However, a more important reason for so proportioning and arranging the parts is that by so doing the strip 16 is permitted to fold up closely against the under side of the body bar 13 with the crossbar extending across the exposed upper ends of the legs and with the strip 16 lying between the folded legs, thus reducing the entire device to relatively small dimensions. If it be desired to stow the device in a still smaller space than that made possible by folding the legs 14 against the bar 13, the legs 14 may be completely removed by disengagement of the wing nuts 45 from their respective pivot bolts 44.

It is to be understood that the details of the invention as herein disclosed, are subject to alteration within the spirit or scope of the appended claims.

I claim:

1. In an assembling device for a trestle including a body bar and a pair of legs, means for pivoting said legs to said body bar adjacent an end thereof to be optionally extended therefrom or folded thereagainst extending toward the other end thereof, and a brace member comprising a brace, means for pivotally securing the upper end of the brace to said body bar, a crossbar secured to the lower end of said brace, and disengageable means at each end of said crossbar for attaching said crossbar to one of said legs, said brace being foldable toward the under side of said body bar to lie between said legs when the legs are folded against the body bar with said crossbar extending across the exposed upper ends of said legs.

2. In an assembling device for a trestle including a body bar and a pair of legs, means for pivoting said legs to said body bar adjacent an end thereof to be optionally extended therefrom or folded thereagainst extending toward the other end thereof, and a brace member comprising a brace, means for pivotally securing the upper end of the brace to said body bar, a crossbar secured to the lower end of said brace, and disengageable means at each end of said crossbar for attaching said crossbar to one of said legs, said brace being foldable toward the under side of said body bar to lie between said legs when

the legs are folded against the body bar with said crossbar extending across the exposed upper ends of said legs, and disposed between said exposed ends and the associated end of said body bar.

3. A trestle comprising a non-metallic body bar and legs extending downwards therefrom, a leg-attaching member comprising horizontal flanges secured to the under side of said bar, and leg flanges extending downwards therefrom, means pivoting each of said legs to one of said leg flanges, a bracing member comprising a brace pivotally secured at one end to the under face of said body bar, and a crossbar rigid therewith and removably engageable at each end with the inner face of one of said legs, said trestle presenting non-metallic top and side areas throughout substantially the entire extent of said body bar.

4. A bracing means, in combination with a trestle comprising a body bar and divergent legs extending downward therefrom, a bracing member comprising a rigid strip, means for attaching one end of said strip to the under surface of said body bar with the strip inclining downwards therefrom toward said legs, a crossbar rigid with the lower end of said strip and extending laterally on both sides thereof, an attaching flange on each end of said crossbar extending at an acute angle therewith to present a face adapted to lie flat against the inner face of one of said legs, and means for attaching each of said flanges to the associated leg.

5. A folding trestle comprising a body bar, an angular member rigid with said bar and having a flange extending downwards therefrom, a leg pivoted to said flange for movement about an axis substantially perpendicular to said flange, the upper inner corner of said leg being rounded about the axis of the pivotal connection whereby said leg is free to swing upwards towards said body bar, and the upper outer corner of said leg engaging the under surface of said bar when in extended relation, and releasable means for retaining said leg in extended position.

6. A folding trestle comprising a body bar, an angular member rigid with said bar and having a flange extending downwards therefrom, a leg pivoted to said flange for movement about an axis substantially perpendicular to said flange, the upper inner corner of said leg being rounded about the axis of the pivotal connection whereby said leg is free to swing upwards towards said body bar, and the upper outer corner of said leg engaging the undersurface of said bar when in extended relation, and a bracing member comprising a strip pivotally secured to the under surface of said body bar, a crossbar at the lower end of said strip and releasable means for attaching each end of

said crossbar to one of said legs to retain the legs swung to fully extended position.

In testimony whereof I have signed my name to this specification.
